CLAIM

The ornamental design for a pet nail trimmer, as shown and described.

DESCRIPTION

FIG. 1 is a front view of a pet nail trimmer, showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a top perspective view thereof;

FIG. 8 is a bottom perspective view thereof; and,

FIG. 9 is a cross-sectional front view taken along and in the direction of line 9-9 in FIG. 5.

The broken lines in the drawings illustrate portions of the pet nail trimmer that form no part of the claimed design.
